GRENADE

Eric Göran Mörner, Stockholm, Sweden

Application May 24, 1934, Serial No. 727,331
In Sweden May 26, 1933

8 Claims. (Cl. 102—29)

The present invention relates to grenades and more particularly to grenades adapted to be thrown by hand of the type adapted to be brought into action irrespective of the part of the grenade against which the impact occurs.

The principal object of the invention is to provide a grenade of the type described comprising two parts which in order to effect ignition are movably connected in relation to each other, said 10 parts forming, after the grenade having been ignited, the active masses thereof, irrespective of the grenade being used for solid, liquid or gaseous charges.

A further object of the invention is to provide 15 a grenade of the type described, in which the movable parts have essentially the same weight and are formed as cup-shaped bodies serving, wholly or in part, as containers for the charge.

A still further object of the invention is to 20 provide a grenade of the type described, in which the movement between the different parts takes place as a rocking movement and/or displacement of the parts in relation to each other, said movement being effected irrespective of the position 25 in which the impact occurs.

A still further object of the invention is to 30 provide a grenade of the type described comprising certain coupling means and securing means, especially a securing rod adapted to be released during the throw by means of a pair of wings 35 swung outwards by the air resistance in order to prevent ignition at undesired time.

At last, the invention is also characterized by 35 certain means for the actuation of the percussion pin and for the insertion of the cartridge in the one or both parts of the grenade.

The invention will be more fully described with 40 reference to the accompanying drawing, other characterizing features of the invention being apparent according as the specification proceeds.

In the drawing:—

Fig. 1 is a longitudinal sectional view of a hand-grenade according to the invention.

Fig. 2 is a cross sectional view of the grenade.

Fig. 3 is a longitudinal sectional view of the 45 grenade illustrating how one body may move in relation to the other and how one body may be divided into two parts.

Fig. 4 is a cross sectional view of a modification 50 of the grenade.

Fig. 5 is a longitudinal sectional view of said modification.

With reference to the embodiment shown in 55 Figs. 1 and 2, the grenade itself forms the members actuating the igniting mechanism, the

grenade being divided into two bodies 1 and 2, each containing an essential portion of the charge 3 and 4, respectively. By this means the main characterizing feature of the invention as far as the ignition is concerned is obtained, viz. that 5 practically the whole weight of the grenade is included in the members movable in relation to each other so as to eliminate any masses inactive for the intended action of the grenade. The bodies may be moved towards each other by a rocking 10 movement and/or a displacement, this being possible by the casing of the body 2 by means of an inwardly directed flange or edge 34 engaging an outwardly directed flange or edge 35 provided on the casing of the body 1. By this means the rocking 15 movement or displacement is effected in a very simple manner irrespective of the direction in which the impact occurs. Evidently, the bodies 1 and 2 are spaced from each other through a distance great enough to render such a movement possible.

Provided in the body 1 is a main-spring 5 which in the embodiment shown is at its ends clamped into a carrier 6 loosely or rigidly arranged in the body 1. A percussion pin 9 is secured to the 25 spring 5. In its stretched position as shown in Figs. 1 and 4, the spring may be actuated by a preferably spherical elevation or shoulder 11 of the body 2.

When the position of the bodies 1 and 2 in relation to each other is changed either by a displacement or, as shown in Fig. 2, by a rocking movement or both, the shoulder 11 causes the spring 5 to move into the position shown in Figs. 2 and 5, resulting in the pin 9 being driven into 35 the cartridge 18 causing the grenade to be brought into action.

The main-spring 5 may with its ends be secured to flaps 7, folded upwardly on the carrier 6, and may be prevented from lateral displacement by flaps 8, folded inwardly at the edge of said carrier. The carrier 6 is provided with a central opening of circular or any other form and having an inner edge 22, against which the spring 5 abuts in its stretched position. By varying the size of the opening in the annular carrier 6 and the dimensions of the spring 5, it is possible within wide limits to vary on the one hand the pressure required to cause the spring 5 to move from its starting position into its end 40 position (shown by dotted lines in Fig. 1), on the other hand the size of the displacement of the point 6 of the spring 5 required to effect said movement and at last the force by which the impact of the spring 5 takes place.

Normally, the bodies 1 and 2 are maintained in definite position in relation to each other by means of a securing rod 10 passed through two diametrically opposed holes 65 in the casing of the body 1 and abutting against the flange 34 of the casing of the body 2, so as to cause said rod also to prevent displacement and/or rocking movements. By this means, the shoulder 11 of the body 2 is prevented from actuating the main-spring 5.

In the embodiment according to Fig. 4, the casing of the body 2 consists of an unflanged member 36 and a displaceable sleeve 37 having a flange 38. Mounted in the open end of the member 36 is a disk 39 having a cylindrical portion 66 and a central portion 40 curved upwardly and provided with a flange 41 bearing on the member 36. The flange 38 is so dimensioned as to permit the upper portion 42 of the grenade (in the position shown) to be inserted into the flange ring 38 and to be maintained in position by the diameter of the flange 43 of the part 42 being greater than that of the opening of the flange ring 38. The part 36 is provided with a mangled edge 44 and the sleeve 37 with a corresponding impression 45.

Mounted above the upwardly curved portion 40 of the disk 39 is a sleeve 45 supporting a percussion pin 47 and provided on its cylindrical shell with holes 67 through which the securing rod 52 may be inserted. The sleeve 45 is adapted to engage a recess 68 provided in the part 42 so as to permit the pin 67 to penetrate into the cartridge after the securing rod 52 having been removed. A spring (not shown in the drawing) may be provided in the recess 68 to press the sleeve 45 against the shoulder 40.

The upper part 42 may be provided with a channel 48 having an upper extended portion 49, in which a nut may be threaded to hold the cartridge in position. The securing rod 52 as well as the securing rod 10 in Fig. 1, may be displaced laterally and removed during the throw. For this purpose two sheet metal halves 53 are arranged around the part 42 and at the left side of the figure rotatably connected by means of a pin 54 secured to outwardly folded flaps 55 on each sheet metal half. Moreover, the securing rod 52 is rotatably mounted on a pin 56. On the other side (right side of the figure) the plates 53 are provided with folded portions 57 spaced from each other and connected with each other by means of a safety-pin-shaped member 58, to which is secured a ring 59 large enough to permit a firm grip of same.

In throwing the grenade, the securing rod must, of course, be capable of being removed so that, when the impact occurs, the pin 47 can penetrate into the cartridge 51. When the grenade is to be thrown, the member 58 is removed by a pull in the ring 59 causing the two halves 53 to be disconnected. During the throw, said halves will open as a pair of wings causing on account of the air resistance the securing rod 52 to be drawn out from the upper part 42 to such an extent that the pin 47 can penetrate into the cartridge. However, this operation requires such a long period of time that, if the grenade falls down too near the thrower, the securing rod will still prevent ignition. The arrangement of the securing rod as above described may be substantially the same, irrespective of a main-spring, as shown in Figs. 1 and 2, or a displaceable member 46 with percussion pin 47 being used. A member 61 corresponding to the disk 39 may pref-

erably be arranged in the upper part 42, said member being held in position for instance by means of an edge 70.

As shown in Fig. 3, it may be conceived to space the bodies 1 and 2 from each other. According to this figure, the bodies 62, 63 are connected by a part 64, which may contain an explosive charge or not and which may be of varying length, if desired, not longer than is required for the relative movement.

The dimensions of the grenade may vary, but it is preferred to adapt its parts in such a manner that the two halves have substantially the same weight and are filled with explosive to the greatest possible extent so as to attain greatest activity of the masses at a relatively small weight. In certain cases it is suitable to form the halves of the grenade from thin metal sheet.

The halves of the grenade need not, of course, have different diameters, but they may have substantially equal diameters. They may have cylindrical shape or form parts of a sphere or truncated cone, but also other embodiments may be conceived.

What I claim is:—

1. A grenade of the type described comprising two hollow bodies containing the complete explosive charge and each of them being open at one end, flanges formed around each of said open ends for uniting said ends in such a way that they may be rockable in all directions in relation to each other, and an ignition device being influenced by the relative movements of said hollow bodies in order to explode the charge on impact against any point of the surface of said bodies.

2. A grenade of the type described comprising two hollow bodies containing the complete explosive charge and each hollow body having one end opened, flanges formed around each of the open ends of said bodies for uniting the opened ends thereof in such a way that said bodies may be rockable in all directions in relation to each other, disks for retaining the charge in said bodies and an ignition device being influenced by the relative movements of said hollow bodies in order to explode the charge on impact against any point of the surface of said bodies.

3. A grenade of the type described comprising two hollow bodies containing the complete explosive charge and each of them being open at one end, flanges formed around each of the opened ends of said bodies for uniting the latter in such a way that they may be rockable in all directions in relation to each other, an ignition device, disks for retaining the charge, and one of said disks being curved so as to form an elevation whereby the relative movement of the bodies causes the ignition device to explode the charge on impact against any point of the surface of said bodies.

4. A grenade of the type described comprising two hollow bodies containing the complete explosive charge and each of them being open at one end, flanges formed around each of said opened ends for uniting said bodies in such a way that they may be rockable in all directions in relation to each other, an ignition device comprising a resilient member under tension being inserted between the opened ends of said bodies and being released by the relative movements of said hollow bodies in order to explode the charge on impact against any point of the surface of said bodies.

5. A grenade of the type described comprising

5 two hollow bodies containing the complete explosive charge and each of them being open at one end, flanges formed around these ends for uniting the bodies in such a way that they may be rockable in all directions in relation to each other, an ignition device comprising a resilient member under tension being inserted between the opened ends of said bodies and being released by the relative movements of said hollow bodies 10 in order to explode the charge on impact against any point of the surface of said bodies, and a carrier for said resilient member arranged in said hollow bodies.

10 6. A grenade of the type described comprising 15 two hollow bodies each containing a portion of the complete explosive charge and each of them being open at one end, intermediate flanges uniting said bodies whereby the latter may be rockable in all directions in relation to said flanges, 20 and an ignition device being influenced by the

relative movements of said hollow bodies in order to explode the charge on impact against any point of the surface of said bodies.

7. A grenade of the type described comprising two hollow bodies each containing a portion of the complete explosive charge, means universally connecting said hollow bodies, and an ignition device arranged to be influenced by the movements of said hollow bodies to effect explosion of the charge on impact against any point of 10 the surface of said bodies.

8. A grenade of the type described comprising two hollow bodies each containing a portion of the complete explosive charge, means universally and telescopically connecting said hollow bodies, 15 and an ignition device arranged to be influenced by the movements of said hollow bodies to effect explosion of the charge on impact against any point of the surface of said bodies.
